Des. 217,552
Patented May 12, 1970

217,552

ORTHODONTIC BUCCAL TUBE OR SIMILAR ARTICLE

Brian W. Lee, 24 Mount Ida Ave., East Hawthorn,
Victoria, Australia 3151

Filed Apr. 22, 1969, Ser. No. 16,846

Term of patent 7 years

Int. Cl. D24—03

U.S. Cl. D24—1

FIG. 1 is a perspective view of an orthodontic buccal tube embodying by new design;

FIG. 2 is a side elevational view thereof;

FIG. 3 is a front elevation thereof;

FIG. 4 is a rear elevation thereof.

I claim:

The ornamental design for an orthodontic buccal tube or similar article, substantially as shown and described.
